UNITED STATES PATENT OFFICE.

OTTO F. KLOETZER, OF WASHINGTON, INDIANA.

FLAG HOLDER AND CLASSIFICATION LAMP.

1,466,034.

Specification of Letters Patent.

Patented Feb. 7, 1922.

Application filed July 10, 1920. Serial No. 395,226.

To all whom it may concern:

Be it known that I, OTTO F. KLOETZER, a citizen of the United States, residing at Washington, in the county of Daviess and

5 State of Indiana, have invented new and useful Improvements in Flag Holders and Classification Lamps, of which the following is a specification.

This invention relates to a novel flag pole 10 and classification lamp for locomotives and the like and the principal object of the invention is to provide means for lighting a lamp and moving a screen before the same when the flag is raised, the screen being the same color as the flag.

Another object of the invention is to make the flags of metal or similar material and to slidably mount them on their staffs and to provide a casing for holding the flags when 20 not in use, the casing being of less length than the staffs.

This invention also consists in certain other features of construction and in the combination and arrangement of the several 25 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a side elevation of the invention with one flag in raised position.

Figure 2 is a longitudinal sectional view.

Figure 3 is a cross sectional view.

Figure 4 is a horizontal section on line 4—4 of Figure 2.

40 Figure 5 is a detail sectional view through the switch.

Figure 6 is a section on approximately line 6—6 of Figure 2.

Figure 7 is a longitudinal sectional view 45 through the lamp carrying member.

Figure 8 is a fragmentary view of the bayonet slots in the lamp carrying member.

Figure 9 is a perspective view of the operating lever for the screen.

50 In these views 1 indicates the casing which is adapted to be secured to each side of the locomotive in any suitable manner. The front end is provided with a window 2 and a similar window 3 is placed in the 55 outer side of the casing adjacent the front end thereof through which the rays of the

lamp, placed in the casing, will pass so that said rays may be seen from a point in front of the locomotive and to either side thereof. The top of the casing is open except the 60 front end thereof where a short cover strip 4 is located, the inner ends of which is provided with a pair of notches 5. The top part of the casing slopes downwardly from the front to the rear as shown. A shaft 6, which 65 may be in the form of a bolt, passes through the upper part of the casing adjacent its front end and the flag staffs 7 and 8 have their lower ends rotatably connected with said shaft. When the shafts are in upright 70 position they will engage the notches 5 and they may be held therein by means of the latch 9 which is hingedly secured to the cover 4 by the clip 10. As will be understood only one of the flags is held in raised 75 position at a time and the latch can be made to engage either staff by swinging it to the right or left. This latch is of substantially U-shape with one end looped to provide a handle as will be seen from Figure 3. The 80 upper end of the rear end of the casing is provided with the notches 11 for receiving the staffs when they are in their lower positions. Each staff carries a flag 12 which is preferably made of metal and is slidably 85 mounted on the staff by having strips 13 bent to form eyes to slidably receive the shaft. The flag is held at the upper end of the staff by means of the spring latch 14 which is similar to the well known umbrella latch. When the flag is not to be used 90 it is moved towards the pivoted end of the staff, the latch being depressed to permit this movement and the staff is lowered until it engages the notch 11 with the flag within 95 the casing as shown in Figure 2. A guiding strip 15 of inverted V-shape is placed in the lower part of the casing for guiding the flags towards the side walls of the casing.

The bottom of the casing is left open so as 100 not to catch and hold rain water and the like.

I provide means for lighting an electric lamp by the raising of the flag, such means consists of an ordinary button switch 16 105 which is carried by a small casing 17 detachably secured to the upper part of the front end of the casing by means of the screws 18. The button part of this switch passes through a hole in the front end of the 110 casing and is adapted to be pressed upon by an arm 19 secured to the base part of

each of the flag staffs, said arm being so arranged that when the flag staff is moved into raised position the arm will depress the button and close the switch thus completing the circuit to the electric lamp 20 which is placed in the casing adjacent the windows 2 and 3. Thus the lamp will only be ignited when one or the other of the flags is in raised position.

I also provide means for displaying a light of the same color as the raised flag. For instance, if green and white flags are being used I provide a pair of screens 21, the transparent portions of which are of green color and said screens cover the windows 2 and 3 when the green flag is in raised position. As soon as the green flag is lowered, however, it will engage the hooked part of a spring rod 22 and move said rod downwardly and this movement of the rod will rock the lever 23 on its pivot 24 and as said lever is connected with the screens by the links 25 said screens will be raised in their guideways 26 above the window openings and thus a white light will be displayed when the white flag is in raised position. As soon as the green flag is raised the weight of the screens will cause the parts to assume a position with the screens covering the window openings and thus display a green light. In order to prevent the flag from coming in contact with the lever and rod I provide a curved shield 27 which is secured to one side of the casing above the pivotal parts of the lever and the rod. As said rod 22 is made of spring metal its hooked end will move away from the side of the casing when the green flag is raised and will project beyond the side of the guide strips 15. This will insure the hooked part being engaged by the green flag when the same is lowered.

I also provide means for removing the electric lamp if the electric system of the train should be disorganized for any reason and for substituting an oil burning lamp. In order to do this I provide a cup-shaped member 28 which carries the lamp socket 29, said socket resting upon an insulated strip 30 which is supported from a base 31 carried by the cup member. The contact member 32 rests upon the insulated strip and has a spring end passing into the bottom of the socket for engaging the central contact of the lamp while the other contact member 33 is connected with the screwed part of the socket and also rests upon the insulated strip. These members 32 and 33 are electrically connected with the switch and a suitable source of electrical supply. The cup-shaped member is detachably secured to the bottom of the casing by fitting over a flange 34 which projects downwardly from the casing and surrounds an opening therein. This flange carries a pair of lugs 35 which are adapted to engage the bayonet slots 36

formed in the cup-shaped member and spring latch members 37 carried by the cup-shaped member engage said lugs and hold the parts against turning movement and thus lock the parts together. If the electric system should be disorganized for any reason it is simply necessary to remove the cup-shaped member and substitute an ordinary oil lantern for the same. A shield 38 is placed in the casing to protect the lamp and its associated parts from the elements.

It will thus be seen that the flags, being made of metal, will last for years thus replacing the flags made of cloth which wear out very quickly or become so soiled that they must be replaced by new ones. The flags of my device remain on the engine at all times and are protected by the casing. When a flag is to be used it is simply necessary to swing its staff into raised position and lock it in this position by the latch member and then shove the flag to the upper end of the staff. This movement of the staff will light the lamp and if it is a green flag the green screens will drop in front of the lamp to give a green light. The lamp socket can be easily removed to place a new lamp therein or to permit an oil lamp to be substituted.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A device of the class described comprising a casing, a shaft passing through the same adjacent the front end thereof, a pair of flag staffs pivoted on said shaft, a slidably mounted flag formed of a sheet of metal on each staff, a latch member on each staff for holding the flag in raised position, said flags being adapted to be moved downwardly so as to enter the casing when the staffs are lowered.

2. A device of the class described comprising a casing, a shaft passing through the casing adjacent the top part of its front end, a pair of flag staffs rotatably connected with said shaft, metal flags carried by said staffs, a notched cover part on the casing, the notches of which receive the staffs when the same are in raised position, a latch member on said cover part for holding the staffs in raised position, the rear end of the casing being notched to receive the staffs when in lowered position.

3. A device of the class described comprising a casing having an open top, a shaft passing through the same adjacent the upper part of its front end, a pair of flag staffs rotatably secured to said shaft, metal flags slidably mounted on said staffs, a

latch member on each staff for holding the flag at the upper end of the staff, a cover part at the front end of the casing having notches therein for receiving the staffs, a 5 latch member on the cover part for engaging either staff for holding the staffs in raised position, the rear end of the casing having notches therein for receiving the staffs when in lowered position and a guiding member 10 in the lower part of the casing of inverted V-shape for separating the flags.

4. A device of the class described comprising a casing having a window therein, a shaft passing through the casing adjacent the upper part of its front wall, a pair of 15 flag staffs rotatably connected with said shaft, flags carried by said staffs, a lamp in the casing, a movable screen in the casing and means for moving the screen to 20 cover the window when one of the flag staffs is raised while permitting the other flag to be raised without affecting the screen.

5. A device of the class described comprising a casing, a shaft mounted therein, 25 a pair of flag staffs pivotally mounted on

the shaft, a pair of windows in the casing, a lamp in the casing adjacent the windows, a pair of movable screens for covering the windows, and means for moving the screens before the windows when one of the flag 30 staffs is in raised position and permitting the same to remain in inactive position when the other flag staff is raised.

6. A device of the class described comprising a casing having a pair of windows 35 therein, a pair of flag staffs pivotally mounted in said casing, a lamp in the casing adjacent the windows, guideways adjacent each window, a screen located in each guideway, a pivoted lever, links connecting 40 the same with the screens, a spring rod connected with the lever and having a hooked end, and a flag on each staff formed of stiff material, one flag being adapted to engage the hooked part of the rod when the flag 45 is lowered to rock the lever to raise the screens from before the windows.

In testimony whereof I affix my signature.

OTTO F. KLOETZER.
